UNITED STATES PATENT OFFICE.

NORTON A. NEWDICK AND WILLIAM E. MOODY, OF COLUMBUS, OHIO, ASSIGNEES TO
JAMES ELLWOOD JONES, OF SWITCHBACK, WEST VIRGINIA.

RAIL-JOINT.

1,357,584.

Specification of Letters Patent.

Patented Nov. 2, 1920.

Application filed November 2, 1918. Serial No. 260,779.

To all whom it may concern:

Be it known that we, NORTON A. NEWDICK and WILLIAM E. MOODY, citizens of the United States, residing at Columbus, in the county of Franklin and State of Ohio, have invented certain new and useful Improvements in Rail-Joints, of which the following is a specification.

This invention relates to rail joints and is specifically directed to an improved type of rail joint designed to be used in mines for the recovering of coal or other mineral. This particular type of joint is further particularly adapted for use in connection with mechanical loading machines wherein it is essential to mount short rail jumpers in position in order that the loading machine may at all times be kept upon the track.

In loading machines generally and those having a sweep movement across the floor specifically, short jumper sections are essential in order that the supporting truck portion may be maintained on the rail and that the sweep portion may remain in contact with the floor. To this end, the main object of my invention resides in a rail joint whose coöperating hinge sections are mounted upon adjacent ends of rail sections and which hinge members are so designed to permit a horizontal pivoting action and at the same time to firmly lock the rails together when the latter are in a position of alinement. In this manner, the rail sections may be temporarily joined and still remain in an angular position with respect to the straight-away track and be out of position of conflicting with the loading machine. After the latter has advanced sufficiently, the rail sections may be swung horizontally to a position of alinement with the straight-away rails and locked in this position by means of suitable fish plates.

The preferred embodiment of our invention is shown in the accompanying sheets of drawings wherein similar characters of reference designate corresponding parts and wherein,

Figure 1 is a top plan view showing the meeting ends of two rail sections, the latter being shown partially broken away, with our hinge members applied, the angular position of these rails being also shown in broken lines.

Fig. 2 is a section taken on line 2—2 of Fig. 1,

Fig. 3 is a section taken on line 3—3 of Fig. 1,

Fig. 4 is a side elevation of the structure shown in Fig. 1, and

Figs. 5 and 6 are detached perspective views of the coöperating hinge members.

The rail sections themselves are designated 1 and 2, the rail 1 forming the portion of the straight-away track and the section 2 represents a jumper section. To these rail sections 1 and 2 there are attached the hinged members 3 and 4 respectively. As is known, the webs of the ends of all rail sections are provided with holes for the application of the ordinary splice plates and my hinge members are attached to certain of these holes by means of the bolt and nut structures shown at 5 and 6 respectively. Both the members 3 and 4 are made of a size to properly fit the web of the rail sections and are of such length that their pivoting point lies directly opposite the line of juncture between the rail sections themselves. The hinge member 3 comprises a body whose side portion 4' fits the rail and ends in a shoulder portion 5' which, when applied to the rail section lies flush with the end of the rail as is illustrated in Figs. 1 and 4. This member 3 is further shaped to present a slotted opening or key way 6' for coöperation with a key mounted upon the member 4. Further, the outwardly projecting flange shown at 7 completely overlies the head of the bolt 5 to protect the latter from any possible abuse. The member 4 is similarly shaped with a vertical side portion 8 which lies against the web of the section 2 and this side portion terminates at its forward end as shown at 9 in a shoulder designed to coöperate with and lie flush against the shoulder 5' on the member 3 when the rail sections are in a position of alinement such as is illustrated in Figs. 1 and 4. The flange portion 10 of the member 4 also overlies the bolt 6 and carries a depending key 11 at its forward end consisting of a stud 11 and a locking foot 12 disposed at an angle to the portion 8. This foot 12 is of a size and shape to enter the key way 6 while the hinge members are in the relative position indicated by the broken lines in Fig. 1 and the stud 11 is of such length that the foot 12 will underlie the metal surrounding the key way 6 when the rails and hinge members are swung to the full line position in

Fig. 1. It will thus be noted that the rail ends are brought into abutting relation and are securely locked against removal when in the full line position as shown in Fig. 1 and at the same time, these hinge members permit of a horizontal swinging movement.

Only one track-way has been shown but it will be understood that the same structure applies to the opposite track-way so that 10 when both rail sections are swung to a position of alinement, they are held in such position by the application of the ordinary type of fish plate applied to opposing rails. In this manner the rail ends are locked together 15 and are held in this locked position against accidental removal by means of the fish plates.

From the foregoing description, taken in connection with the accompanying sheets of drawings it will be apparent that we have provided a type of rail joint possessing a marked degree of utility when used in connection with a loading machine or any type of machine which is mounted upon track 20 wheels and which requires a certain amount of space forward of the rail ends to operate upon. By means of this structure, the track wheels may operate, for instance, upon the pair of tracks 1 to permit its forward end 25 to have a sweep movement over the unobstructed floor in front of the machine. During its operation, jumper sections equipped with the hinge members 4 may be dropped in position by passage of the key 11 through 30 the key way 6 and allowed to remain in substantially a right angular position with respect to the sections 1. After the machine has advanced a distance requiring additional trackage, this additional trackage may be 35 supplied by simply swinging the jumper sections 2 about their hinge keys toward 40 each other, this movement being limited by the abutting relation between the track ends and between the shoulders 5 and 9. The 45 jumper sections are then held against lateral displacement by the application of the ordinary type of fish plate whereupon the machine may be permitted to advance upon the newly supplied trackway.

50 What we claim is:

1. In a rail joint, the combination with

55 a pair of rail sections, of a pair of separable hinge members directly secured to the respective meeting ends of said rail sections, and means whereby said members may be detachably locked together by a horizontal swinging movement on the part of at least one of said sections.

2. In a rail joint, the combination with 60 a pair of rail sections, of a pair of hinge members secured to the respective ends of said rails, and means carried by said members for permitting their interlocking connection when said members have assumed a horizontal angular position with respect to 65 each other and capable of being swung horizontally to a position of alinement, said means holding said members firmly together when in such latter position.

3. In a rail joint, the combination with a 70 pair of rail sections, of a pair of hinge members secured to the respective ends of said rails, one of said members having a slot 75 therein, the other of said members being provided with a depending vertically arranged pivot pin, and a laterally projecting foot on the bottom of said pin arranged at such angle that said foot will pass through said member when the rail sections are angularly arranged with respect to each other 80 but forms a lock against detachment of said sections when they are swung horizontally to a position of alinement.

4. In a rail joint, a pair of rail sections, 85 each of said sections being provided at their adjoining ends with a laterally extending offset shelf portion, the shelf portion of one 90 of said sections being provided with a vertically disposed pivoting element arranged to be received within a co-operative slot formed in the shelf portion of the adjacent rail section, whereby said sections are subject to horizontal swinging movement, and an offset projection provided upon the lower end 95 of said element and operating to lock said sections together when the latter assume a position of longitudinal alinement.

In testimony whereof we affix our signatures.

NORTON A. NEWDICK.
WILLIAM E. MOODY.
